UNITED STATES PATENT OFFICE.

MARKWELL S. PURDY AND HERMANN ALBER, OF CORNING, NEW YORK;
SAID PURDY ASSIGNOR TO SAID ALBER.

ALCOHOL DISINFECTING-LAMP.

SPECIFICATION forming part of Letters Patent No. 399,078, dated March 5, 1889.

Application filed May 6, 1887. Serial No. 237,373. (No model.)

To all whom it may concern:

Be it known that we, MARKWELL S. PURDY, a citizen of the United States, and HERMANN ALBER, a citizen of Germany, residing at Corning, in the county of Steuben and State of New York, have invented a new and useful Improvement in Alcohol Disinfecting-Lamps, of which the following is a specification.

Our invention relates to an improvement in alcohol disinfecting-lamps; and it consists in the peculiar construction and combination of devices, that will be more fully set forth hereinafter, and particularly pointed out in the claims.

15 In the drawings, Figure 1 is a vertical sectional view of a lamp embodying our improvements. Fig. 2 is an elevation of the burner.

A represents a lamp-bowl, which is provided on its upper side with a collar or neck, 20 B. This neck is formed integral with the bowl by a reduced extension thereof. C represents a circular concavo-convex disk which rests upon the upper side of the neck of the lamp and closes the same, and downward 25 through the central opening in the said disk extends a wick-tube, D, which is secured to the disk at a point about one-third its length from its upper end. E represents a series of vertical supports, which are made of spring- 30 wire, are secured to disk C, and project upward above the upper end of the wick-tube a suitable distance. The said wire supports are provided with hooks F at their upper ends, adapted to engage the lower side of a 35 truncated conical heater or cap, G, which is provided with perforations in the sides and is made of platinum.

H represents an extinguisher, that is adapted to be inserted over the neck of the lamp, 40 so as to inclose the burner and entirely cut off the supply of air therefrom.

The operation of our invention is as follows: The lamp-bowl is nearly filled with pure alcohol, and a wick is inserted in the wick-tube and extended down into the alcohol and saturated with the same. The extinguisher is removed and the wick is lighted. The flame from the wick soon heats the platinum cap until the same becomes incandescent. 45 The extinguisher is then placed over the

burner and the neck of the bowl and extinguishes the flame, and the extinguisher is then immediately removed from the lamp, and the vapor from the alcohol, rising upward in the cap G, comes in contact therewith and becomes decomposed by contact with the heated platinum, and the heat generated by the decomposition of the alcoholic vapor keeps the platinum cap in an incandescent condition.

55 So far as we are aware, the devices heretofore provided have employed a spiral coil or cylinder of platinum surrounding the wick. This device was easily bent or broken, became only partially incandescent, and ceased 60 to glow whenever the wick touched it. In our device these difficulties are overcome, as the shape is such that the ascending vapors must strike the cap, while the upper end of the wick, being below or just on a level with the 65 lower end of the cap, cannot touch the same.

70 We desire in no sense to increase the brilliancy of a flame. Our purpose is to keep a cap of thin platinum incandescent (for the purpose specified) without using a flame, except as explained, to render the platinum incandescent. Then the flame is extinguished.

75 We are aware that spongy platinum has been used to light streams of hydrogen or of hydrocarbon gases, and in various flames 80 platinum has been introduced to acquire greater brilliancy. All of these we disclaim. As our lamp is more particularly designed for sick-rooms, the platinum would most probably be shaded, as the disinfecting and purifying 85 qualities are those alone wanted.

Having thus described our invention, we claim—

1. The herein-described alcohol disinfecting-lamp, comprising the bowl A, having its 90 central portion extended up and reduced to form the integral neck B, the disk C, resting on the upper edge of the neck, the wick-tube D, extending down through an opening of the disk and secured at an intermediate point of 95 its length thereto, and the vertical supports E, secured to the disk C and extended upward beyond the wick-tube, so as to hold the cap out of contact with the wick, and having hooks at their upper ends, the perforated 100

platinum cap G, supported detachably by the hooks above the wick-tube, and the extinguisher H, as set forth.

2. The bowl A, the cap G, of perforated sheet metal or platinum, and the extinguisher H, to extinguish the flame, whereby when the extinguisher is removed after the flame is extinguished the vapor from the alcohol, rising up, comes in contact with the cap and be-
10 comes decomposed, and the heat generated by the decomposition of the alcohol-vapor keeps the platinum cap in an incandescent condition, as set forth.

3. The bowl A, disk C, and wick-tube D, combined with the supports E, extending up
15

from the disk above the wick-tube and having the hooks F, and the removable platinum or sheet-metal cap G, having its base or open end resting on the top of the supports within the hooks, whereby the cap will be held above the 20 wick, so that the latter cannot come in contact with the cap, as set forth.

In testimony that we claim the foregoing as our own we have hereto affixed our signatures in presence of two witnesses.

MARKWELL S. PURDY.
HERMANN ALBER.
